[57] CLAIM

The ornamental design for a combined door handle and lock plate unit, as shown and described.

DESCRIPTION

FIG. 1 is a front elevational view of a combined door handle and lock plate unit showing my new design; FIG. 2 is a right side elevational view thereof, the left side being a mirror image;

FIG. 3 is a rear elevational view thereof;

FIG. 4 is a top plan view of the lock plate shown separately for ease of illustration, the bottom being a mirror image;

FIG. 5 is a top plan view of the door handle also shown separately for ease of illustration;

FIG. 6 is a bottom plan view thereof.

FIG. 1

FIG. 2

FIG. 3

FIG. 4

FIG. 5
